BENJAMIN B. BLOCK, OF LOS ANGELES, CALIFORNIA, ASSIGNOR OF ONE-HALF TO
MARY AVERY SCHERFEE, OF LOS ANGELES, CALIFORNIA.

AIR-HEATER FOR INTERNAL-COMBUSTION ENGINES.

1,400,015.

Specification of Letters Patent. Patented Dec. 13, 1921.

Application filed September 9, 1918. Serial No. 253,210.

To all whom it may concern:

Be it known that I, BENJAMIN B. BLOCK, a citizen of the United States, residing at Los Angeles, in the county of Los Angeles and State of California, have invented a new and useful Air-Heater for Internal-Combustion Engines, of which the following is a specification.

The object of this invention is to provide improved means for heating air passing to the carburetor of an internal combustion engine.

The accompanying drawings illustrate an embodiment of my invention, and referring thereto:

Figure 1 is a partly sectional front elevation of the air heating means.

Fig. 2 is a section on line 2—2 in Fig. 1.

In the drawing, *a* designates an internal combustion engine, having an intake pipe or manifold 1 and exhaust pipes 2. The carburetor *b* is connected to said air intake pipe and is provided with an air inlet pipe 3, which leads from a pre-heater *c*. Said pre-heater comprises an outer casing 4, an inner casing 5 and an intermediate casing 6. Outer casing 4 is divided by longitudinal partitions 7 into lower and upper chambers constituting first and second exhaust-receiving chambers, and the lower chamber is provided near one end with an air inlet 8, and communicates at its other end, through a passage 8' with the chamber above the partitions 7, such upper chamber being in communication, at the end remote from the passage 8', with a passage 9 leading to the chamber within inner casing 5. The exhaust pipes 2 communicate with pipes 10 leading to the lower part of casing 6 which makes a tight contact with the inner casing 5 at each side, so as to divide the casing 6 into upper and lower chambers. At one end of the intermediate casing 6 a passage 11 is provided through which the exhaust gases may pass from the lower to the upper chamber in such casing, and the other end of the upper chamber of casing 6 is connected to a pipe 12 for carrying away the exhaust. With the above described construction, the exhaust receiving passages or chambers in casing 6 are surrounded by the air heating

passages or chambers in the outer casing 4 and surround the air superheating passage or chamber in the inner casing 5. This construction insures maximum efficiency in heating as the heat from the exhaust chambers can not pass directly to the outer air, but must pass either to the outer or to the inner air chamber, and the air after passing around the exhaust chamber and being partially heated by the heat which would otherwise be lost by radiation from the outer walls of the exhaust chamber, then passes to the superheating chamber wherein it is surrounded by the inner walls of the exhaust chamber and is thereby raised to a higher temperature than is possible in the outer chamber, which is exposed to radiation on the outer side thereof.

In the operation of the apparatus, air is drawn from air inlet 8 through the lower air heating chamber in casing 4, the passage 8', the upper air heating chamber in casing 4, passage 9, inner casing 5 and pipe 3 to the carburetor. In passing through the air heating chambers in casing 4 the air is heated and it is then superheated in passing through the inner casing 5, such heating being effected by the heat of the exhaust gases passing through the passages in casing 6. The pre-heated air passes through the carburetor, wherein it takes up fuel from the distributing device, the heated condition of the air insuring vaporization of such fuel, even when fuel of low volatility is used.

What I claim is:

An air pre-heater for internal combustion engines comprising an outer casing, an intermediate casing within the outer casing, partitions between the outer and intermediate casings dividing the space between said casings into first and second air heating chambers, an inner casing within the intermediate casing and constituting a superheating chamber, and dividing the space within the intermediate chamber into first and second exhaust-receiving chambers, said first air heating chamber having an air inlet at one end and connecting at its other end with the second air heating chamber, and said super-heating chamber having an outlet at one end and connecting at its other end with

the second heating chamber at the end thereof which is remote from its point of communication with the first air heating chamber, said first exhaust-receiving chamber having inlet means for receiving exhaust gases and the second exhaust-receiving chamber having an outlet at one end and

communicating at its other end with the first exhaust-receiving chamber.

In testimony whereof I have hereunto subscribed my name this 30th day of August, 1918.

BENJAMIN B. BLOCK.
